CAM GRINDING APPARATUS

Clarence J. Green, Worcester, Mass., assignor to
 Norton Company, Worcester, Mass., a corpora-
 tion of Massachusetts

Application September 2, 1942, Serial No. 456,975

5 Claims. (Cl. 51—101)

This invention relates to grinding machines and more particularly to a cam grinding machine.

One object of this invention is to provide a simple and thoroughly practical grinding machine for grinding cams. Another object of the invention is to provide a cam grinding apparatus in which a cam for imparting motion in two directions may be accurately ground. Another object of the invention is to provide a cam grinding apparatus in which the cam being ground is moved longitudinally and laterally to accurately produce a pre-determined cam contour. A further object of this invention is to provide a cam grinding apparatus having a rock bar which is arranged for a simultaneous rocking about in axis and moved longitudinally in an axial direction to grind a pre-determined cam contour. Other parts will be obvious or in part pointed out hereinafter.

The invention accordingly consists in the features of construction, combinations of elements, and arrangement of parts as will be exemplified in the structures hereinafter described, and the scope of the application of which will be indicated in the following claims.

In the accompanying drawings, in which is shown one of various embodiments of the mechanical features of this invention,

Fig. 1 is a front elevation of a grinding machine embodying this invention;

Fig. 2 is a fragmentary plan view of the grinding machine shown in Fig. 1 having parts broken away and shown in sections to clarify the illustration;

Fig. 3 is a fragmentary elevation showing the arrangement of the rock bar together with the work support and the master cams for controlling the movements thereof;

Fig. 4 is a fragmentary staggered sectional view on an enlarged scale, taken approximately on the line 4—4 of Fig. 1; and

Fig. 5 is a fragmentary detailed view showing the arrangement of the rock bar.

A cam grinding machine as illustrated in the drawings comprising a base 10 which serves as a support for a longitudinally traversable table 11. The table 11 is supported on a V-way 12 and a flat way 13 formed on the upper surface of the base 10. The table 11 is arranged so that it may be traversed longitudinally along the base 10 by means of a manually operable traversing mechanism comprising a hand wheel 14 which is supported on the outer end of a shaft 15. A gear 16 is mounted on the inner end of the shaft 15 and 55

meshes with a gear 17 mounted on a rotatable shaft 18 which is journaled in suitable bearings (not shown) in the base end. The shaft 18 also supports a gear 19 which meshes with a rack bar 20 depending from the under side of the table 11.

5 A stop mechanism is provided for locating the table 11 in a pre-determined fixed position for a grinding operation. The stop lug 25 is fixedly mounted on the base 10 and is arranged to be engaged by a pair of adjustable stop dogs 26 and 27. The stop dogs 26 and 27 are supported by T-slot 28 formed in the front edge of the table 11. The stop dogs 26 and 27 are each provided with an adjustable stop screw 29 and 30 respectively by means of which the table 11 may be precisely located to position the work piece to be ground in a pre-determined position with relation to the grinding wheel.

20 The base 10 also serves as a support for a transversely movable wheel slide 32 which is arranged to slide transversely relative to the base 10 on a V-way 33 and a flat way 34. The wheel slide 32 supports a rotatable wheel spindle 35 in journal bearings (not shown). A grinding wheel 36 is mounted on one end of the wheel spindle 35 and a driving pulley 37 is mounted on the other end thereof. The driving pulley 37 is connected by a driving belt 38 with a suitable source of power, such as, for example an electric motor (not shown) mounted on the upper surface of the wheel slide 32.

25 A wheel feeding mechanism is provided for moving the grinding wheel 36 transversely comprising a rotatable feed screw 40 which is supported in the bearing (not shown) in the base 10. A half nut 41 depends from the under side of the wheel slide 32 and meshes with the feed screw 40. The feed screw 40 is provided with an integral reduced cylindrical portion 42 which projects 30 from the front of the machine base. A gear 43 is mounted on the outer end of the feed screw shaft 42 which in turn meshes with a gear 44. The gear 44 is mounted on the inner end of a rotatable shaft 45. A manually operable feed wheel 46 is mounted on the outer end of the shaft 45. A micrometer feed adjusting mechanism 47 is provided with a stop abutment 48 which is arranged to engage a pivotally mounted stop pawl 49 which is in turn pivotally supported in the front of the machine base 10. It will be readily apparent from the foregoing disclosure that by a manual manipulation of the feed wheel 46, the grinding wheel 36 may be moved transversely either toward or from the work supporting table 11 as desired. By adjustment of the micrometer

feed adjustment 47, the grinding wheel 38 may be moved into a precise position to grind the work piece to the desired diameter. For further details of this feeding mechanism reference may be had to the expired U. S. patent to C. H. Norton No. 762,838 dated June 14, 1904.

The work supporting table 11 serves as a support for a rock bar 50. The rock bar 50 is provided at its opposite ends with a pair of axially aligned trunnions 51 and 52 which are journaled in bearings formed within the brackets 53 and 54 projecting upwardly from the work table 11. The rock bar 50 is arranged so that it may be rocked about the trunnions 51 and 52 and is also arranged so that it may be moved longitudinally; that is in an axial direction with respect to the trunnions 51 and 52 bearing rotation of a work piece to impart a combined transverse and longitudinal movement to a work piece being ground in a manner to be hereinafter described.

The rock bar 50 is provided with a rotatable head stock or master cam spindle 55 which is journaled in upwardly projecting brackets 56 and 57 which are formed integral with the rock bar 50. The spindle 55 is provided with a work center 58 which engages and supports one end of a work piece 59 to be ground. A footstock 60 is adjustably supported on the rock bar 50 and is provided with a footstock center 61 which engages and supports the opposite end of the work piece 59. The headstock spindle 55 is also provided with a face plate 62 having a driving pin 63 which is arranged to drivingly engage a work dog 64 mounted on/or adjacent to the left hand end of the work piece 59. The headstock or master cam spindle 55 is provided with a master cam 65 which is arranged to engage a master cam roller 66. The master cam roller 66 is supported on a rotatable shaft 67 which is in turn rotatably journaled in bearings (not shown) in the brackets 68 and 69 which are formed integral with the brackets 56 and 57 respectively.

A motor drive is provided for the headstock or master cam spindle 55 comprising an electric motor 70 which drives through a gear reduction unit contained within the casing 71 to rotate a universal joint 72 which connects with the left hand end of the spindle 55 (Fig. 2). It will be readily apparent from the foregoing disclosure that a rotary motion of the master cam or headstock spindle 55 will transmit a rotary motion to the workpiece 59. At the same time a rotary motion is imparted to the master cam 65 which is yieldably maintained in operative contact with the roller 66 so that the motion of the cam 65 will impart a rocking motion to the rock bar 50 and thus cause the axis of the work piece 59 to move towards and from the periphery of the grinding wheel 38 to generate a pre-determined contour on the work piece 59 being ground.

In order to grind special cam shapes having both a transverse as well as an axial movement to be imparted thereby, a suitable mechanism is provided to simultaneously impart an axial movement to the rock bar 50 during its oscillation. This mechanism may comprise a master cam 75 having a face cam generated thereon. A master cam roller 76 is provided and is rotatably supported on a shaft 77 which is supported within a casing or frame 78 surrounding the headstock of the machine. A compression spring 80 is interposed between a flanged plate 81 fastened to the bracket 54 at one end and a collar 82 adjustably connected by a rod 83 with the trunnion 52 in a manner so that the spring 80

5 exerts a pressure tending to move the rock bar in a direction toward the right (Figs. 1, 2, 3) so as to maintain the operative side face of the cam 75 in operative engagement with the master cam roller 76.

In order that the master cam roller 76 may be maintained in a pre-determined relationship with the cam 75 during the transverse oscillation of rock bar 50, the shaft 77 is preferably supported by two pairs of rollers 85 and 86 and 87 at one end and 88, 89, and 90 at the other end. The shaft 77 thus supported is free to move in a transverse direction. In order that the shaft may move in timed relation with the rock bar 50, a strap 91 surrounds a portion of the master cam or headstock spindle 55. The strap 91 connects by a stud 92 with the end of the shaft 77. It will be readily apparent from the foregoing disclosure that when the rock bar 50 is oscillated about its pivotal axis by means of the cam 65 and follower 66, the strap 91 being rotatably supported on the spindle 55 will move the master cam roller 76 transversely so as to maintain it in a pre-determined relationship with the operative face of the cam 75. During the rotary motion of the spindle 55 to impart a transverse oscillation of the rock bar 50, the cam 75 will in turn impart a simultaneous longitudinal movement to the rock bar so that a cam face having the surfaces 100 and 101 to be ground may be accurately generated as desired.

20 In order to maintain the master cam 65 in operative engagement with the master cam roller 66 a tension spring 102 is contained within a casing 103 supported by a bracket 104 on the end of the headstock casing 78 (Fig. 2). The upper end of the spring 102 is connected to the lower end of an adjusting screw 104. The lower end of the adjusting screw is connected to a stud 105 which is pivotally supported by a stud 106 carried by a bracket 107. The bracket 107 is in turn pivotally connected by a stud 108 with an arm 109 which is formed integral with the rock bar 50. The right hand face of the casing 103 is open (Fig. 1) so that as the rock bar is moved in an axial or longitudinal direction by the cam 75, due to the pivotal connection at the lower end of the spring 102 a constant tension will be exerted by the spring 102 uniformly to maintain the master cam 65 in operative contact with its follower roller 66.

25 The operation of this improved cam grinding apparatus will be readily appreciated from the foregoing disclosure. Assuming all of the parts to have been previously set up, a work piece 59 having cam faces 100 and 101 to be generated is mounted in position on the work supporting centers 58 and 61 respectively with the work driving pin 63 in engagement with the work driving dog 64. The table 11 is then traversed longitudinally so that the work piece 59 is in a desired and pre-determined relationship with the grinding wheel 38 after which the table dogs 26 and 27 are locked in adjusted position. The table may then be precisely adjusted to a further extent by manipulation of the stop screws 28 and 30. The drive motor 70 is then started to impart a rotary motion of the headstock or master cam spindle 55 which in turn rotates the work piece 59 and at the same time through the master cams 65 and 75 respectively, imparts a transverse oscillating movement to the rock bar 50 and at the same time imparts a simultaneous longitudinal movement to the rock bar 50 so that the grinding wheel will generate the cam

faces 100 and 101 which are arranged to transmit transverse and longitudinal movements. Wheel may be fed transversely to grind the faces 100 and 101 to the desired and pre-determined extent by a manual manipulation of the feed wheel 48.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a cam grinding apparatus having a transversely movable rotatable grinding wheel, a rotatable work supporting member including a rotatable spindle, means positively to rotate said spindle, a longitudinally and transversely movable support for said work supporting member, means including a cam on said spindle and a follower to impart a transverse movement to said work supporting member, independent means including a second cam on said spindle and a second follower simultaneously to impart a longitudinal movement to said work supporting member to facilitate grinding an irregular cam face, a transversely movable support for said second follower, and means to maintain said latter follower in a predetermined relationship with said second cam during transverse movement of said longitudinally and transversely movable support.

2. In a cam grinding machine having a transversely movable rotatable grinding wheel, a rock bar which is pivotally supported about an axis parallel to the axis of the grinding wheel, a rotatable work support on said bar including a rotatable master cam spindle and a footstock, means including an electric motor to rotate said spindle and work piece, means including a master cam on said spindle and a follower to impart a transverse rocking movement to said bar, means including a second master cam on said spindle and a slidably mounted follower roller which are arranged to impart a longitudinal axial movement to the rock bar, said cams being shaped and timed to impart a combined simultaneous longitudinal and transverse movement to generate an irregular cam face, a transversely movable support for said slidably mounted follower roller, and means to maintain said follower in a predetermined relationship with said second cam during oscillation of said rock bar.

3. In a cam grinding apparatus having a base, a transversely movable rotatable wheel thereon, a longitudinally movable work table on said base, means to locate and hold said table in a predetermined grinding position, a rock bar pivotally supported on said table, a rotatable work support on said rock bar including a rotatable spindle to support and rotate a work support, means including a cam on said spindle and a follower to impart a transverse movement to said work support, means including a second cam on said spindle and a second follower simultaneously to impart a longitudinal movement to said work support, means to maintain said second cam in operative engagement with said second follower, and means to maintain said second follower in a predetermined relationship with said second cam during transverse movement of said work support.

4. In a cam grinding apparatus having a base, a transversely movable rotatable grinding wheel thereon, a longitudinally movable work table on said base, means to locate and hold said table in a predetermined grinding position, a longitudinally movable rock bar pivotally supported on said table, a rotatable work support on said rock bar including a rotatable spindle to support and rotate a work support, means including a cam on said spindle and a follower to impart a transverse movement to said work support, means including a second cam on said spindle and a second follower simultaneously to impart a longitudinal movement to said work support, means to maintain said second cam in operative engagement with said second follower, and means to maintain said second follower in a predetermined relationship with said second cam during transverse movement of said work support.

5. In a cam grinding apparatus having a base, a transversely movable rotatable grinding wheel thereon, a longitudinally movable work table on said base, means to locate and hold said table in a predetermined grinding position, a longitudinally movable rock bar pivotally supported on said table, a rotatable work support on said rock bar including a rotatable spindle to support and rotate a work support, means including a cam on said spindle and a follower to impart a transverse movement to said work support, means including a second cam on said spindle and a second follower simultaneously to impart a longitudinal movement to said work support, means to maintain said second cam in operative engagement with said second follower, and means to maintain said second follower in a predetermined relationship with said second cam during transverse movement of said work support.

6. In a cam grinding apparatus having a base, a transversely movable rotatable grinding wheel thereon, a longitudinally movable work table on said base, means to locate and hold said table in a predetermined grinding position, a longitudinally movable rock bar pivotally supported on said table, a rotatable work support on said rock bar including a rotatable spindle to support and rotate a work support, means including a cam on said spindle and a follower to impart a transverse movement to said work support, means including a second cam on said spindle and a second follower simultaneously to impart a longitudinal movement to said work support, means to maintain said second cam in operative engagement with said second follower, and means to maintain said second follower in a predetermined relationship with said second cam during transverse movement of said work support.

7. In a cam grinding apparatus having a base, a transversely movable rotatable grinding wheel thereon, a longitudinally movable work table on said base, means to locate and hold said table in a predetermined grinding position, a longitudinally movable rock bar pivotally supported on said table, a rotatable work support on said rock bar including a rotatable spindle to support and rotate a work support, means including a cam on said spindle and a follower to impart a transverse movement to said work support, means including a second cam on said spindle and a second follower simultaneously to impart a longitudinal movement to said work support, means to maintain said second cam in operative engagement with said second follower, and means to maintain said second follower in a predetermined relationship with said second cam during transverse movement of said work support.

CLARENCE J. GREEN.
